United States Patent Office

Des. 196,689
Patented Oct. 22, 1963

196,689

HAND FIN

Joseph E. O'Reilly, 4101 San Jacinto, Houston, Tex.

Filed June 15, 1962, Ser. No. 70,559

Term of patent 3½ years

(Cl. D71—1)

I claim:

The ornamental design for a hand fin, as shown.
